COMBINED DRINK MUDDLER AND SIPPER

Ralph S. Gordon, 150 Beach 127th St.,
Belle Harbor, N.Y. 11694

Filed Mar. 2, 1970, Ser. No. 21,672

Term of patent 3½ years

Int. Cl. D7—99

U.S. Cl. D94—3

Fig. 1.

Fig. 2.

Fig. 3.Fig. 4.

FIG. 1 is a front perspective view of a combined drink muddler and sipper showing my new design;

FIG. 2 is a rear perspective view thereof;

FIG. 3 is a front perspective view of a combined drink muddler and sipper showing another form of my new design wherein the sipping tube has been omitted; and

FIG. 4 is a rear perspective view thereof.

I claim:

The ornamental design for a combined muddler and sipper, substantially as shown and described.
